CLAIM

The ornamental design for flame resistant fabric, as shown
and described.

DESCRIPTION

FIG. 1 is a perspective view of a first embodiment of a flame
resistant fabric according to the present design.
FIG. 2 is a top perspective view thereof; and,
FIG. 3 is a top perspective view of a second embodiment of
a flame resistant fabric according to the present design.
The broken lines in the drawings depict the boundaries of the
claim and form no part thereof.
